(57) **CLAIM**

The ornamental design for the sign cover, as shown and described.

DESCRIPTION

FIG. 1 shows a top perspective view of the sign cover.

FIG. 2 shows a bottom perspective view of the sign cover.

FIG. 3 shows a front elevation view of the sign cover, the back side being a mirror image thereof.

FIG. 4 shows a left side elevation view of the sign cover, the right side being a mirror image thereof.

FIG. 5 shows a top plan view of the sign cover; and,

FIG. 6 shows a bottom plan view of the sign cover.

The broken lines shown in the drawings illustrate environment, and form no part of the claimed design.
